(57) **CLAIM**

The ornamental design for a vehicle wheel cover, as shown and described.

DESCRIPTION

FIG. 1 is a front perspective view of a front face of a vehicle wheel cover;

FIG. 2 is a front view thereof; and

FIG. 3 is a right side view thereof;

FIG. 4 is a top side view; and,

FIG. 5 is a bottom side view thereof.

A left side view has been omitted because this is identical to the right side view shown in FIG. 3.
